UNITED STATES PATENT OFFICE.

JOHN A. CALDER, OF TORRINGTON, CONNECTICUT, ASSIGNOR TO THE TORRINGTON COMPANY, OF TORRINGTON, CONNECTICUT, A CORPORATION OF CONNECTICUT.

RIVET-CUTTING DEVICE.

Application filed July 13, 1921. Serial No. 484,406.

To all whom it may concern:

Be it known that I, JOHN A. CALDER, a citizen of the United States, residing at Torrington, in the county of Litchfield, State of Connecticut, have invented certain new and useful Improvements in Rivet-Cutting Devices, of which the following is a description, reference being had to the accompanying drawing and to the figures of reference marked thereon.

The invention relates to new and useful improvements in rivet cutting devices, and more particularly to a rivet cutting device which operates to cut the rivet after it has been placed in the article to be riveted at each side of the article and leaving only sufficient projecting portions of the rivet for the heading thereof.

An object of the invention is to provide a machine of the above type with devices movable into position for holding the article to be riveted and devices which are automatically movable subsequent to the holding devices for cutting the rivet.

A further object of the invention is to provide a machine of the above type, wherein the holding devices move in a direction at right angles to the direction of movement of the rivet cutting devices.

A still further object of the invention is to provide a machine of the above type with means for positioning the rivet so that it is free from engagement by the cutting devices as the cutting devices are moved relative to each other for engaging and holding the article preliminary to cutting.

A still further object of the invention is to provide a machine of the above type, wherein the rivet positioning means is automatically withdrawn when the cutters are moved forward for cutting the rivet.

These and other objects will in part be obvious and will in part be hereinafter more fully described.

In the drawings which show by way of illustration one embodiment of the invention—

Figure 1 is a side view of a machine embodying my improvements;

Figure 2 is a front view of the same and prior to the actuation of the cutting members;

Figure 3 is a similar view of the machine but after the cutting members have been actuated to cut the rivet;

Figure 4 is a plan view of the machine; Figure 5 is a view on the line 5—5 of Figure 1;

Figure 6 is a view partly in side elevation and partly in section from the right of the machine;

Figure 7 is a view showing more or less diagrammatically the position of the cutters and the positioning plate when the needle is first placed in the machine;

Figure 8 is a similar view but showing the upper pair of cutters lowered into holding engagement with the needle;

Figure 9 is a similar view but showing the positioning plate retracted and the cutters moved forward for severing the rivet.

Figure 10 is an enlarged side view of a portion of one of the cutting members;

Figure 11 is a similar view but showing a modified form of cutting member.

The invention is directed broadly to a machine for cutting a rivet after it has been placed in the article and at each side of the article preparatory to the forming of heads at each end of the rivet. The machine is particularly adapted for cutting the rivet preparatory to the riveting of a latch into a knitting needle. The cutting of the rivet is accomplished by two co-operating pairs of cutters. These cutters are preferably mounted so as to move horizontally relative to each other when cutting the rivet. The lower pair of cutters is fixed and has no vertical movement. The upper pair of cutters is moved vertically in position for holding the article in which the rivet has been placed subsequent to the movement of the cutters relative to each other for cutting the rivet.

Positioning means is provided for positioning the rivet away from the cutting members when it is initially placed in the machine so that when the movable pair of cutting members are moved down to engage the article to hold the same, they will not disturb the rivet. This positioning means for the rivet is automatically withdrawn when the cutters are moved forward to sever the rivet.

Referring more in detail to the drawings, the improved rivet cutting machine consists of a supporting base 1 on which is mounted a bracket 2. Said bracket is provided with an outwardly extending arm 3. Mounted to slide on the bracket 2 is a movable head 4.

Said movable head 4 has a dovetail recess formed therein which receives a dovetailed projecting portion 6 carried by the bracket 2. A wear plate 7 is provided which is adjustably supported by bolts 8-8 and the wear plate is for the purpose of taking up any wear between the movable head 4 and the bracket 2. Said movable head 4 is provided with an outwardly extending arm 9 which is spaced above the arm 3. There is a lower pair of cutting members 10 and 11 and an upper pair of cutting members 12 and 13. The cutting members 10 and 11 are mounted on the outwardly extending arm 3. 10 The cutting member 10 is stationary and has no movement whatever. The cutting member 11 is mounted in a slide 14 which is adapted to reciprocate in guide-ways formed in the arm 3. Said guide-way is dovetailed 15 in cross section and the reciprocating member 14 is also dovetailed in cross section. A plate 15 which is secured by clamping bolts 16-16 to the arm 3 forms the outer wall of the dovetailed guiding recess for slide 14 20 and this plate 15 may be shifted by means of the vertical adjustable stop screws 17-17, so as to take up any wear between the walls of the guiding recess and the slide 14. The holes through which the screws 16-16 pass 25 are enlarged for this purpose. A spring 18 which is in the form of a single coil with projecting arms bears at one end against a portion of the arm 3 and at its other against the slide 14 and normally holds the slide 30 moved to its extreme position away from the stationary cutter, which is the position shown in Figure 2.

The cutter 12 is fixed to the movable head 4 and held thereon by means of a clamping plate 19. Said cutter moves up and down with the movable head, but has no horizontal movement. The cutter 13 is carried by a slide 20 which is adapted to reciprocate in a suitable guide-way formed in the movable head 4. Said guide-way is similar to the guide-way for the slide 14 and the plate 21 forms the outer wall of the guide-way. Said plate is held in position by screws 22 and adjustable stop screws 23 are for the purpose of taking up wear between the walls of the guide-way and the slide 20. A spring 24 similar in construction to the spring 18 normally moves the slide 20 outwardly to its extreme limit which is the position shown in Figure 2.

The movable head 4 is raised to its extreme upper position by means of a spring 25. Said spring is seated at its upper end in a recess 26 in the head 4 and at its lower end in a recess formed in the main portion 2 of the standard. Said movable head 4 is lowered by means of a rock lever 27. Said rock lever 27 is pivoted at 28 to a supporting bracket 29 which is secured by suitable screws to the main standard 2. Said rock

lever is provided with a forwardly projecting arm 30. Said forwardly projecting arm 30 is provided with a threaded opening through which an adjustable bolt 31 passes. Said bolt bears on the upper end of the movable head 4. The arm 30 is split at its free end into said opening for the adjustable bolt 31 and a clamping screw 32 serves as a means for clamping the adjustable bolt 31 and holding it in adjusted positions. The rock lever 27 at the lower end of its arm carries a roller 33 which bears on the face of a cam 34 rigidly secured to a shaft 35. The shaft 35 is mounted in a bracket 36 secured by bolts 37-37 to the base portion 1. 75 This cam 34 is provided with a rounded shoulder 38 which engages the lever when the shaft is moved from the position shown in Figure 1 and in a counter-clockwise direction and causes the movable head 4 to be 80 depressed.

The shaft 35 is given a limited oscillation by means of an arm 39 which is rigidly secured to the shaft 35. Said arm 39 at its rear end is provided with a pin 40 which extends into an elongated slot 41 in an arm 42. The arm 42 is fixed to a shaft 43 carried by a bracket 44, secured to the table carrying the rivet cutting machine. Also, mounted on the shaft 43 is an arm 45 which carries a roller 46 adapted to bear on a cam 47 carried by a shaft 48. A spring 49 normally holds the arm 45 in contact with the cam and as the shaft 48 rotates the arm 45 will be oscillated and through the connecting devices referred to will oscillate the shaft 35 through a limited distance. The shaft 35 will be moved in a counter-clockwise direction positively, while the spring 49 will retract the parts returning the shaft and the cam carried thereby to the position shown in Figure 1. It will thus be seen that when the shaft 48 rotates the cam 47 will positively swing the arm 45 which will positively move the shaft 35 in a counter-clockwise direction. This will positively swing the rock lever 27 and positively move the movable head 4 downwardly. As soon as the cam 47 releases the arm 45, the spring moves said arm to the left, as viewed in Figure 1, and this will move the shaft 35 in a clockwise direction, releasing the rock lever 27 and permitting the spring 25 to raise the movable head 4.

The cutters are moved for cutting the rivet by means of a lever 50. Said lever 50 is mounted to swing freely on a vertical pivot 51 which is fixed to the lugs 52-52, and the lugs 52-52 are in turn carried by the standard 2. Said lever 50 at its forward end carries two adjustable screws 53-54. These screws project through the arm, as clearly shown in Figures 2 and 3 and are adapted to bear respectively against the ends of the slides 20 and 14. The lever

50 is slotted from its outer end into the threaded openings which carry the adjustable screws 53 and 54 and a bolt 55 passing through the slotted end of the lever serves as 5 a means for clamping the screws 53 and 54 in their adjusted positions.

The cam 34 is provided with a cam plate 56 on the side thereof. The upper end of this cam plate 56 is beveled at 57. This 10 beveled end of the cam plate 56 is so positioned as to engage the extreme left-hand end of the lever 50. Said left-hand end of the lever 50 is provided with a projecting nose 58 for this purpose. It will thus be 15 seen that when the shaft 35 is rotated the lever 50 will be oscillated so as to cause the screws 53 and 54 to engage the slides carrying the movable cutters and move said cutters forward in order to 20 cut the rivet. When the shaft 35 is moved in a clockwise direction, then the lever 50 is released and the springs 18 and 24 operating through the slides 14 and 20 respectively will swing the lever 50 to the 25 position shown in Figure 2.

Attached to the movable head 4 is a bracket arm 59. Said bracket arm is secured by a clamping bolt 60 to said movable head. This bracket arm extends downwardly and across a plane lying between the 30 pairs of cutting members. The purpose of this bracket arm is to position the article carrying the rivet for cutting.

As above noted, the invention is particularly adapted for the cutting of a rivet 35 which is used for securing the latch to a knitting needle. The needle is indicated at N in the drawings and the rivet at r. This rivet is a threaded rivet and is threaded into an opening in the cheeks of the latch 40 needle and through the latch and when it is first put into the needle said rivet has projecting ends which facilitate the placing of the rivet in the needle. These ends have 45 to be cut off at each side of the needle just the distance from the side cheeks of the needle so that the ends of the remaining portion of the rivet may be riveted down. When the needle is placed in the machine, 50 it is placed against the bracket arm 59, as shown in Figure 6. The clamping plate 61 which holds the stationary cutter 10 is provided with a guide plate 62 which is inclined to the path of reciprocation of the slide 14 55 and extends to a point adjacent the cutting edge of the cutter 10. The purpose of this inclined guide plate is to guide the rivet so as to position the rivet between the cutting members. As noted, the rivet projects beyond the side faces of the needle, and one of the projecting ends of the rivet will engage 60 this guiding plate 62 which is just below the cutters, and will insure that the projecting portions of the rivet are positioned 65 between the cutters.

There is also a positioning plate 63 which normally extends up in front of the cutting edge of the cutting member 10 and this positioning plate is directly in rear of the rear edge of the guide plate 62 and serves 70 to hold the rivet away from the cutting edge not only of the lower cutting member 10 but out of the path of the downward movement of the upper cutting member 12. This positioning plate 63 is carried by an arm 64 75 which is pivoted at 65 to a bracket 66 carried by the base plate 1 of the machine. Said bracket is secured to the base plate by screws 67. A spring 68 rigidly secured to the bracket 66 bears on the underface of 80 the arm 64 and normally raises the arm to the position shown in Figures 2, 7 and 8 with the positioning plate up in front of the cutting edge of the cutting member 10. Adjustably secured to the arm 64 is a cam plate 85 69 which has an upwardly projecting cam shoulder 70. This upwardly projecting cam shoulder 70 lies in the path of movement of the extreme outer end of the lever 50 and is so positioned that on the first forward 90 movement of the lever 50 to operate the cutters the cam shoulder 70 will be engaged by the lever and the arm 64 swung downwardly to the position shown in Figure 3. A stop screw 71 carried by the arm engages 95 the under portion of the projecting arm 3 and limits the upward movement of the positioning plate 63.

In order that the rivet, after being cut 100 may exceed in length the thickness of the cheek of the needle and provide sufficient stock to form the rivet heads, I have formed the cutting edges of the cutters back from the surfaces of the cutters which engage and hold the needle. In Figure 10, I have 105 shown the cutters 11 as ground at 11^a, so as to set the cutting edge 11^b back from the surface 11^c which engages and holds the needle. It is understood that the other cutters are similarly constructed. The cutaway surface in Fig. 9 is parallel with the surface 11^c and is set back a sufficient distance to provide the desired projecting length of rivet to form the heads. In Figure 10 the cutter is ground so as to form a 110 beveled surface 11^d and thus the cutting edge 11^d is set back.

The operation of my machine is thought 115 to be obvious from the description given above. The latch needle end is put into the machine when the parts are in the position shown in Figure 2.

The upper pairs of cutters are then 120 raised and the movable slides carrying the cutters are retracted. The bracket arm 59 125 positions the shank of the needle and determines the inner position of the needle. In other words, the operator holds the needle shank substantially parallel with the direction of movement of the cutters and 130

moves it into the machine by a sidewise movement until the needle shank strikes the positioning bracket arm 59. The rivet projecting below the needle engages the inclined plate 62 and will be guided to a position between the cutters and will also be held away from the cutting edges of the cutters 10 and 12 by the positioning plate 63. As the shaft 35 rotates, the movable head 4 moves downwardly and this occurs before any inward movement of the cutters takes place. This downward movement of the head 4 brings the upper pair of cutters into clamping or holding engagement with the needle. The needle is not however very tightly gripped but just enough to hold it in place and the amount of gripping of the needle can be readily adjusted by adjusting the bolt 31. Inasmuch as the rivet is some distance away from the cutting edge of the cutter 12, it can be moved down into clamping position of the needle without bending the rivet or stripping the edge thereof or in any way interfering with the rivet which projects upwardly from the shank of the needle. After the needle is clamped then by continued rotation of the shaft 35 the lever 50 is oscillated which operates through lever 64 on positioning plate 63 and withdraws it from its position between the lower pair of cutters and also operates on the slides 14 and 20 and causes the movable cutters to co-operate with the horizontal stationary cutters and sever the rivet both above and below the needle. After the shaft 35 has completed its oscillation and the rivet has been severed, then it oscillates in the opposite direction and as it moves in the opposite direction the cutters will be retracted and the movable head will be raised and the needle released. At the same time the positioning plate 63 moves into position for the placing of the next needle.

It is obvious that minor changes in the details of construction and the arrangement of the parts may be made without departing from the spirit of the invention as set forth in the appended claims.

Having thus described the invention, what I claim as new and desire to secure by Letters Patent, is:

1. A rivet cutting machine including in combination, two pairs of cooperating cutters, means for operating the cutters in the respective pairs for cutting the rivet at each end thereof, and means for moving one pair of cutters bodily toward and from the other for clamping the article carrying the rivet to be cut and thus holding the rivet relative to the cutters for the cutting action thereon.

2. A rivet cutting machine including in combination, two pairs of cooperating cut-

ters, means for operating one of said pairs for cutting the rivet, automatic means for moving the other pair of cutters bodily relative to the first-named pair of cutters for clamping the article carrying the rivet to be cut, and for moving the cutters to cut the rivet.

3. A rivet cutting machine including in combination, two pairs of cutters, means for moving one pair of cutters toward the other for holding the article carrying the rivet to be cut, a positioning plate for positioning the rivet away from the cutters, and means for automatically moving said positioning plate away from the cutting region and for operating the cutters to cut the rivet.

4. A rivet cutting machine including in combination, a standard, a projecting arm carried thereby, a pair of cutters mounted on said arm, a movable head carried by the standard, a pair of cutters mounted on said movable head, means for moving the head to cause the upper pair of cutters to hold the article carrying the rivet to be cut, and means for moving one cutter in each pair for cutting the rivet.

5. A rivet cutting machine including in combination, a standard, an arm projecting therefrom, a pair of cutters carried by said arm, one of which is stationary and the other of which is movable, a movable head, a pair of cutters carried thereby, one of which is stationary on the head, and the other of which is movable, means for moving the head to cause the cutters to hold the article carrying the rivet to be cut, and means for operating the movable cutters to cut the rivet.

6. A rivet cutting machine including in combination, a standard, an arm projecting therefrom, a pair of cutters carried by said arm, one of which is stationary and the other of which is movable, a movable head, a pair of cutters carried thereby, one of which is stationary on the head, and the other of which is movable, means for moving the head to cause the cutters to hold the article carrying the rivet to be cut, means for operating the movable cutters to cut the rivet, a positioning plate for positioning the rivet normally away from the cutters, and means for moving said plate subsequent to the action of the cutters.

7. A rivet cutting machine including in combination, a standard, an arm projecting therefrom, a pair of cutters carried by said arm, a movable head, a spring for normally raising the head, a pair of cutters carried by said head, a rock lever, means carried by the rock lever for engaging the head for moving the same downwardly to cause the cutters to hold the article carrying the rivet to be cut, an oscillating shaft, a cam carried thereby and adapted to actuate said rock le-

ver, a lever for actuating the cutters to cut the rivet, a second cam carried by said shaft adapted to actuate said lever subsequent to the downward movement of the head to cause the cutters to cut the rivet.

8. A rivet cutting machine including in combination, a standard, an arm projecting therefrom, a pair of cutters carried by said arm, a movable head, a spring for normally raising the head, a pair of cutters carried by said head, a rock lever, means carried by the rock lever for engaging the head for moving the same downwardly to cause the cutters to hold the article carrying the rivet to be cut, an oscillating shaft, a cam carried thereby and adapted to actuate said rock lever, a lever for actuating the cutters to cut the rivet, a second cam carried by said shaft adapted to actuate said lever subsequent to the downward movement of the head to cause the cutters to cut the rivet, a positioning plate for engaging the rivet to position the same back from the cutting edges of the cutters, yielding means for raising the positioning plate to its normal operative position for engaging the rivet, and means actuated by the lever operating the cutters for withdrawing said positioning plate prior to the movement of the cutters to cut the rivet.

9. A rivet cutting machine including in combination, a standard, an arm projecting therefrom, a pair of cutters carried by said arm, a movable head, a spring for normally raising the head, a pair of cutters carried by said head, a rock lever, means carried by the rock lever for engaging the head for moving the same downwardly to cause the cutters to hold the article carrying the rivet to be cut, an oscillating shaft, a cam carried thereby and adapted to actuate said rock lever, a lever for actuating the cutters to cut the rivet, a second cam carried by said shaft adapted to actuate said lever subsequent to the downward movement of the head to cause the cutters to cut the rivet, a positioning plate for engaging the rivet to position the same back from the cutting edges of the cutters, yielding means for raising the positioning plate to its normal operative position for engaging the rivet, means actuated by the lever operating the cutters for withdrawing said positioning plate prior to the movement of the cutters to cut the rivet, and an inclined guide plate for directing the rivet in front of said positioning plate.

10. A rivet cutting machine including two pairs of cutters, means for supporting one pair of cutters whereby it may be moved toward and from the other for engaging the article carrying the rivet to be cut, a single lever for operating the cutters to cut the rivets, a rock lever for actuating the supporting means for the movable pair of cut-

ters, a positioning plate for positioning the rivet away from the cutting edges of the cutters, an inclined guide plate for directing the rivet in front of the positioning plate, means whereby said lever for actuating the cutters operates to position the plate prior to the movement of the cutters to cut the rivet, an oscillating shaft, means for positively moving said oscillating shaft in one direction and for yieldingly moving said shaft in the opposite direction, a cam carried by said shaft and adapted to engage the rock lever when positively moved for lowering the movable cutters into contact with the article carrying the rivet to be cut, a second cam carried by said shaft and adapted to engage said lever for operating the cutters, said cams being so disposed that the cutters are first lowered into engagement with the article and the cutters are subsequently operated to cut the rivet.

11. A rivet cutting machine including in combination, two pairs of cutters, a movable head carrying one pair of cutters, a rock lever for moving said head downwardly, an adjustable bolt carried by the rock lever and engaging said movable head, a spring for raising said movable head, and means for operating the cutters after the head has been lowered to hold the article for cutting the rivet.

12. A rivet cutting machine including two pairs of cutters, one of which is movable for clamping the article holding the rivet to be cut, a bracket arm adapted to engage the article for positioning the same between the cutter, a positioning plate for positioning the rivets away from the cutting edges of the cutter, an inclined guide plate for directing the rivet in front of the positioning plate, means for moving the pairs of cutters toward and from each other, and means for operating the cutters to cut the rivet.

13. A rivet cutting machine including in combination, two pairs of cutters, means for moving one pair of cutters toward the other for holding the article carrying the rivet to be cut, and means for operating the cutters to cut the rivet, said cutters engaging the article having their cutting edges set back from the article to provide sufficient rivet stock to form the heads.

14. A rivet cutting machine including in combination, two pairs of cutters, means for moving one pair of cutters toward the other for holding the article carrying the rivet to be cut, and means for operating the cutters to cut the rivet, said cutters being ground on their faces engaging and holding the article so as to form cutting edges set back from said holding surfaces.

In testimony whereof, I affix my signature.

JOHN A. CALDER.
